Drug composition having antirheumatic and analgesic
indications containing as active ingredients dextro-
propoxyphene and phenyl butazone, and treatment
comprising administering as active ingredients dextro-
propoxyphene and phenyl butazone.

DRUG COMPOSITION

The present invention relates to a drug compound of antirheumatic and analgesic indication.

It has been known, following the synthesis by H. Stenzel in 1946, that phenyl butazone (1,2-diphenyl-3,5-dioxo-4-n-butyl-pyrazolidine) has analgesic and antirheumatic effects. Until the present time, phenyl butazone was considered to be the most effective anti-rheumatic drug, apart from the steroids. However, the administration of phenyl butazone in effective dosages is accompanied by serious side effects, caused by its inhibiting action on certain enzymatic reactions taking place in the body.

It is also known that these side effects can be avoided by using a combination of a reduced dosage of phenyl butazone with an analgesic.

From British Pat. No. 1,081,105 is known a drug which has anti-inflammatory and analgesic effects and which consists of a combination of butazone (1-phenyl-3,5-dioxo-4-n-butyl-butazolidine) and d-propoxyphene (1,2-diphenyl-2-propionoxy-3-methyl-4-dimethylaminobutazone hydrochloride), the analgesic effect of the d-propoxyphene component being magnified through its combination with butazone. From this patent disclosure it is further known that this kind of magnification effect is not obtainable with combinations of phenyl butazone with propoxyphene, and that these combinations are therefore not suitable for medication. Yet, there has existed a long-standing basic need for such a combination, especially of phenyl butazone because of its very strong antirheumatic indication in comparison to butazone, with analgesic agents in which the magnifying characteristics would be present.

In the past, the magnifying effects of phenyl butazone have been obtained only in combination with such drugs as morphine, codeine, or methadone. However, these combinations have the drawback that they involve the risk of patient addiction, and for this reason they are not very desirable.

The objective underlying the present invention was therefore the discovery of a drug based on phenyl butazone which retains the known antirheumatic effects of phenyl butazone, while having a strong analgesic indication at reduced dosage, so that the known side effects are eliminated, or at least reduced.

In spite of the commonly held belief that combinations of phenyl butazone with propoxyphene are not suitable for medication purposes, the above objective has now been unexpectedly attained by the discovery of a drug compound consisting of phenyl butazone and dextro-propoxyphene.

The simultaneous administration of phenyl butazone and dextro-propoxyphene was found to produce an ex-

traordinarily pronounced magnification of the analgesic effects, in addition to a prolongation of the analgesia itself. It has thus become possible to make the therapeutic dosages of the active ingredients in the drug compound small enough to substantially eliminate the known side effects.

In the following the invention will be explained in more detail with reference to several embodiments.

In a series of writhing tests performed on mice it was found that especially favorable results are obtained with a drug compound in which dextro-propoxyphene and phenyl butazone are present in a molar ratio of 1 to 2. These results are reflected in a table given below in which some of the readings obtained in the tests are listed by way of example. The effectiveness of the different drug compounds is stated as a percentage in relation to the 1 to 2 molar ratio.

Table 1

Reciprocal values of ED_{50} values of various mixtures of dextro-propoxyphene-HCl with phenyl butazone, given as a percentage of the ED_{50} value of a mixture with a molar ratio of 1 to 2, which is equal to 100 percent (writhing test on mice):

Molar ratio: d-propoxyphene to phenyl butazone	45 min		90 min	
	30	30	30	30
1 to 16	57 %		75 %	
1 to 8	81 %		85 %	
1 to 4	94 %		97 %	
1 to 2	100 %		100 %	
1 to 1	74 %		98 %	

This optimal mixture in a molar ratio of phenyl butazone to dextro-propoxyphene of 2 to 1 has proved to have novel and interesting pharmacological effects, as indicated by the tests described below:

In an analgesia test (writhing test on mice) performed under optimal conditions, a mixture (B) of dextropropoxyphene with phenyl butazone when compared to dextropropoxyphene alone (A), produced an analgesia magnification of up to 4.2-fold, as shown by a comparison between the ED_{50} values of (A) and (B), taken 180 minutes after oral administration. The values which correspond to various other times elapsed are listed in Table 2 below:

Table 2

ED_{50} values obtained in writhing tests on mice, at times elapsed between 15 and 240 minutes after oral administration of compounds A, C, and B (values for B are computed from readings for C):

Compound	15	30	60	120	180	240
(A) dextro-propoxyphene	24	23	31	71	135	150
(B) dextro-propoxyphene in mixture - computed from (C)	13	11	16	27	32	37
(C) mixture of dextro- propoxyphene with phenyl butazone, molar ratio 1 to 2	33	30	53	72	85	97
(D) phenyl butazone	350	360	390	650	650	900
	ED_{50} in mg per kg body weight duration in minutes					

A magnification of effectiveness is evident and can be computed from the ED_{50} values of Table 2. This magnification is illustrated in Graph I.

Graph I

Effectiveness magnification factor obtained through comparison of ED_{50} values of (A) and (B) in Table 2

Graph I also shows another interesting result with respect to therapy: 37 mg of dextro-propoxyphene-hydrochloride in pure form are sufficient for an analgesia lasting approximately 70 minutes, whereas the same dosage of dextro-propoxyphene in the mixture disclosed above assures an equally effective analgesia, even after 4 hours of elapsed time (see Graph II).

Graph II

Table 3

	Number of cases	very good	good	fair	ineffective
Degenerative spine syndromes, with or without radiculitis, such as:	197	49	115	19	14
spondyl-arthritis					
morbus Bechterew					
osteochondrosis					
HWS-syndrome, occipital syndrome, thoracic syndrome					
LWS-syndrome, lumbo-sacral syndrome					
discus prolapse					
Arthroses	44	9	24	9	2
Arthritides	35	2	31	1	1
Neuralgias, neuritis	46	14	24	5	3
Abdominal rheumatisms	22	8	12	-	2
Periarthritides	14	5	5	2	2
Post-traumatic conditions	55	24	30	1	-
Total	413	111	241	37	24

45

In 82.2 percent of these cases the results observed by the examining physicians were listed as either very good or good. The extraordinary analgesic effects achieved are particularly evident in the category of post-traumatic conditions. The treatment results obtained in other typical categories of the rheumatoid group indicates that the antirheumatic effects of phenyl butazone in the disclosed combination fully match previously observed effects of treatment with phenyl butazone in its known large dosage, even though its dosage in the disclosed combination is substantially reduced.

It has thus become possible to offer successful anti-rheumatic therapy, in spite of a reduction of the phenyl butazone dosage to one-third of its previously required dosage.

I claim:

1. Drug composition having an antirheumatic and analgesic indication containing as active ingredients dextropropoxyphene and phenyl butazone in mole ratio between 1 to 1 and 1 to 8.

2. The drug composition of claim 1 wherein the mole ratio of dextro-propoxyphene to phenyl butazone is between 1 to 1 and 1 to 4.

3. The drug composition of claim 1 wherein the mole ratio of dextro-propoxyphene to phenyl butazone is 1 to 2.

4. The method of treating rheumatic disorder which comprises administering to a patient suffering from rheumatic disorder, an effective antirheumatic and analgesic amount of dextro-propoxyphene and phenyl butazone in mole ratio between 1 to 1 and 1 to 8 as active ingredients.

5. The process of claim 4 wherein the mole ratio of dextro-propoxyphene to phenyl butazone is between 1 to 1 and 1 to 4.

6. The process of claim 4 wherein the mole ratio of dextro-propoxyphene to phenyl butazone is 1 to 2.
